UNITED STATES PATENT OFFICE

FREDERICK U. CONARD, OF BRIDGEPORT, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed April 4, 1928. Serial No. 267,226.

The present invention relates to means in a portable typewriting machine for centering and locking the platen-carriage and for locking the escapement-mechanism against displacement, preparatory to closing the cover of the carrying case. It is usual to center the platen-carriage by releasing the same from the escapement-mechanism by operation of the carriage-release lever, and permitting a spring-motor to pull the carriage to the left against a stop, by a separate operation.

It is a feature of the present invention to provide means which are effective by one convenient operation for releasing the carriage from the escapement-mechanism, centering and locking the released carriage on the main frame, and locking the escapement-rack in released position.

In carrying out my invention, as applied to an Underwood portable typewriting machine, a downwardly movable carriage-centering lever is positioned at the right side of the platen-carriage and may be pivoted upon the platen-shaft. In the form of the invention illustrated, an operative connection is preferably provided between the carriage-release lever and the centering lever, which is effective, upon operation of the latter, to release the escapement-rack. Thereupon the released carriage and the centering lever are pulled leftwardly by the usual spring-motor until the depressed lever abuts against a stop. A leftwardly-extending locking tongue on the lever is arranged to engage under a keeper for retaining the lever in its carriage-releasing position. Upon opening the case again, the platen-carriage may be moved to the right to withdraw the tongue from under the keeper, and the stop-lever is returned to normal position by a spring, and the escapement-rack is restored to its pinion.

Another feature of the invention in its preferred form resides in the positioning of the usual carriage-release lever and the carriage-centering lever side by side, both pivoted about the same fulcrum with a one-way operative connection between them, whereby operation of the centering lever operates the release-lever, but operation of the latter does not affect the centering lever.

Other features and advantages will hereinafter appear.

In the accompanying drawings, Figure 1 is a fragmentary, diagrammatic, plan view, shown partly in section, of an Underwood typewriting machine having the present invention applied thereto, which machine is encased in a usual carrying case, part of which is shown broken away to expose the right side of the machine. In this view, the position of the carriage, prior to being centered, is illustrated by a dot-and-dash representation of the carriage at the right of the case.

Figure 2 is a fragmentary cross-sectional view through an Underwood portable typewriting machine having my invention applied thereto, the locking lever being shown in ineffective position.

Figure 3 is a fragmentary perspective view of the right-hand side portion of an Underwood portable typewriting machine having my invention applied thereto, the locking lever being shown pressed down in operated position, and about to engage the track of the platen-carriage.

Figure 4 is a view similar to Figure 2, the locking lever being shown in locked relation with the angle-piece of the track of the platen-carriage. In this view, a fragmentary portion of the usual case is shown in position around the machine.

Figure 5 is a disassembled perspective view of the locking lever of the present invention and other parts at the left side of the platen-carriage which co-operate with the locking lever.

The present invention is illustrated as applied to an Underwood portable typewriting machine in which types 10 strike against a platen 11 carried on a shaft or axle 12. The left-hand end of the shaft is journaled in a left-hand end-plate 13 of a platen-carriage 14, which includes a right-hand end-plate 15 and a cross-plate 16 fastened between the side plates 13 and 15. The right-hand end of the platen-shaft 12 is journaled in devices supported on the right-hand end-plate 15, which will be more fully described hereinafter. The above described parts, except the

shaft-journaling devices on the plate 15, may be the same as like parts in a standard Underwood portable typewriting machine.

When a type 10 strikes against a worksheet, not shown, around the platen 11, the carriage 14 is letter-spaced by escapement mechanism including a feed-rack 17, which meshes with a pinion 18 fixed to a concentric escapement-wheel 19. The rack 17 may be 5 floatingly mounted in a well-known way on a swingable arm 20 of a bell-crank 21 pivoted on a pin 21^a in the right-hand end-plate 15, and on a pivoted arm, not shown, which is fastened to the left-hand end-plate of the 10 rack.

The platen-carriage is released from the escapement-mechanism by swinging the rack 17 upwardly from the pinion 18. For attaining this end, the bell-crank is provided 15 with an upwardly-extending arm 22 terminating in a round knuckle-end which is engaged in a socket-like end 23 of a usual carriage-release lever 24, which is pivoted about a bushing 25, having an axial hole 26 for 20 serving as a journal for the right end of the platen-shaft 12. The bushing may be adjustably mounted perpendicularly to the end-plate 15 by having its right end fastened rigidly to an arm 27, which is pivoted about a 25 pin 28 in the end-plate, the other end 29 being rounded over for engagement in an adjustable slide 30. The construction and operation of the arm 27 and slide 30 are more fully described in the co-pending application of William A. Dobson, filed November 28, 1925, Serial No. 71,876. The upper end of the release lever 24 is urged clockwise by a spring 31, and a finger 32 on the lever strikes against a usual unreaching flange 33 of the end-plate 15, and arrests the lever in normal position to 30 bring the rack 17 into operative engagement with the pinion 18.

A track for the platen-carriage may include a usual angle-plate 34, fastened between the sides 35 of a shift-frame 36, and a usual angle-plate element 37 formed in the upper end of a sheet-metal back plate 38 fastened rigidly between the sides 35 of the shift-frame 36 at the rear of the platen 11. The track-element 37 includes a forwardly and upwardly inclined flange 39. The cross-plate 16 of the platen-carriage is mounted between the plate 34 and the element 37, the long edges of the plate terminating in usual angle-pieces 40, which co-operate with the angle-plate 34 and angle-plate element 37 to form raceways for anti-friction elements 41.

The shift-frame 36 may be mounted for 60 case-shift movement on a usual main frame 42 in the same way as is disclosed in the above-mentioned Dobson application. By this construction the shift-frame does not move laterally. To draw the carriage 14 leftward on the shift-frame, a usual spring 65

43 may be employed and be connected to the carriage by usual devices not shown.

For centering the carriage 14, a centering member, generally designated as 50, is displaceably mounted on the carriage 14 and may take the form of a lever having a round hole 51 through its pivot-end for engaging around the bushing 25, the lever 50 being disposed against the lever 24. A collar 52 slips loosely over the bushing to abut against the lever 50, and is held in place thereagainst by a usual hub 53 on a right-hand head-piece, not shown, of the platen 11. A short portion 54 of the lever 50 extends upwardly alongside the release lever 24 (Figure 2) and thence 70 extends rearwardly adjacent a vertical plane through the front edge of the flange element 39. The lever there makes a right-angle bend 75 to the left, for a purpose to appear presently. After extending leftwardly a short distance, the lever makes another right-angle bend 80 to the rear and extends in that direction slightly past a rock-shaft 57, which forms a part of the usual feed-roll release-mechanism of the typewriting machine. 85 Thence a section 58 of the lever extends upwardly and is also bent leftwardly to lie in a plane substantially perpendicular to the plane of the portion of the lever in front of it. An upper portion 59 of the section 58 90 is bent rearwardly at 60 to form a conveniently positioned finger-piece for depressing the lever 50. It will be noted that the finger-piece 59 is placed adjacent the right end of the carriage where an operator may reach 100 it with an easy, natural movement of her right hand, accustomed as it is to reaching the nearby carriage-release lever. This finger-piece extends over the usual rear portable cross-rod 61, striking the same when 105 depressed, and arrests the downward movement of the lever 50.

A short integral lug 62 on the lever-portion 54 extends to the right, and normally engages closely against the forward edge of 110 the carriage-release lever 24, a short distance above the bushing 25. When the lever 50 is depressed the lug 62 swings counterclockwise and moves the lever 24 with it, which effects the disengagement, in the usual way, 115 of the rack 17 and the pinion 18. Thereupon the spring 43 will draw the carriage and the lever 50 to the left.

For arresting the moving carriage, a lug 63 is integrally joined to the lower edge of 120 the lever 50, substantially opposite the right end of the flange 39, and extends downwardly a distance approximately equal to the thickness of the flange, and is thence bent at a right angle to the left. The rearwardly-extending finger-piece 59 is positioned for engaging the cross-rod 61 and arresting the downward movement of the lever 50 when the leftwardly bent portion of the lug 63 comes just below the flange 39, in which no 125 130

sition it will be substantially parallel to the flange. An operator's finger 65, pressing lightly on the finger-piece 59, is effective to maintain the lug 63 in effective position for engaging the flange 39 while the carriage 14 is moving to the left. The downwardly-extending portion of the lug 63 will abut against the right end of the flange 39, and the leftwardly-extending portion of the lug 10 will be disposed under the flange.

To lessen the chance of the left end of the lug 63 striking the right end of the flange, a left end portion 66 of the lug may be bent slightly downward (Figures 3 and 5). Upon removing the finger 65 a tensile spring 67, having one end fastened through a hole in the lever 50, between the bends 55 and 56, and the other end fastened through a hole in the superjacent flange 33, is effective to swing the lever upward until the lug 63 is stopped squarely against the under side of the flange 39, which, in effect, locks the lever 50 in carriage-arresting relation to the shift-frame 36. In some cases, it may be necessary, as illustrated in Figure 3, to cut away a short section of the right end of the flange 39, in order that the latter may engage the lug 63 just when the carriage 14 is accurately centered on the main frame 42.

In an Underwood portable typewriting machine, it is usual to position a feed-roll-release lever 68 adjacent the right-hand end-plate 15 of the carriage 14 adjacent the rear side thereof. To avoid interference with the lever 68 by the finger-piece 59, the aforesaid leftward bend 55 is made in the body of the lever 50. It will be noted that the lug 63, which directly receives the blow, due to arresting the moving carriage 14, is joined to the lever 50 a short distance to the rear of the leftwardly-extending portion between the bends 55 and 56. It will also be noted that the portion of the lever 50 disposed forwardly from the bend 55, is removed from the end-plate 15 a distance equal to the thickness of the arm 27 and the carriage-release lever 24. To transmit the strain caused by stopping the moving carriage from the lug 63 to the rigid end-plate 15, a short integral lug 69 is provided on the lower edge of the lever 50, a short distance in front of the bend 55, and is bent to the right and terminates very closely adjacent the left face of the end-plate 15. The hole 51 in the fulcrum 50 end of the lever 50 fits loosely over the bushing 25, permitting the lever to swing a small amount sidewise without bending when it moves up against the flange 39, and the end of the lug 69 is forced up against the right face of the end-plate 15, and stops further movement of the lever and the carriage. The forward or pivotal end of the lever 50 is held by the collar 52 against a tendency to swing leftward when the lug 69 strikes the end-plate 15.

It will be noted that to center and lock the carriage 14 on the machine by the above-described means requires only one easy operation, a depression of the conveniently placed finger-piece 59. After the carriage 14 is centered, a cover 70, of a carrying case generally designated as 71, may be placed over the machine and locked to a base 72 to which the main frame 42 is usually attached.

When the cover is in position over the carriage 14, which has been centered by the devices of the present invention, the right-hand wall of the cover will be disposed in close proximity to a usual finger-wheel 73 at the right end of the platen, and will prevent rightward movement of the carriage, and thus prevent release of the lever 50.

To prevent up-and-down movement of the shift-frame 36 while the machine is in its case, two pads 74 of soft, spongy rubber may be fastened to the under side of the top of the cover 70 so as to bear down on each end of the platen-carriage 14 when the cover is locked in place on the base 72. The case 71 and pads 74 may be like the case and pads disclosed in the patent to George W. Campbell, No. 1,639,761, dated August 23, 1927.

The present invention, while disclosed as applied to an Underwood portable typewriting machine, can be easily redesigned to be applied to other makes of typewriting machines without involving invention.

Variations may be resorted to within the scope of the invention, and portions of the improvements may be used without others.

Having thus described my invention, I claim:

1. In a typewriting machine, the combination with a laterally fixed shift-frame, a platen-carriage movable in letter-feed direction and return, an escapement-mechanism, and a carriage-moving motor, of a carriage-centering lever on said carriage yieldingly held in ineffective position and movable to effective position for engagement with said frame, means effective upon operation of said lever for releasing said carriage from said escapement-mechanism to permit said motor to move said carriage leftwardly, said lever and said frame co-operating to arrest the movement of said carriage when it is centered on said machine, a locking member on said lever for engaging said frame and retaining said lever in effective carriage-arresting engagement with said frame, said engagement holding said carriage disengaged from said escapement-mechanism, and a case for said machine including a cover fitting over said machine in close proximity to its sides and preventing rightward movement of said carriage, said engagement of said lever and said frame being releasable, after removal of said cover, by movement of said carriage to the right.

2. In a typewriting machine, the combination

tion with a platen-carriage movable in letter-feed direction and return, and a track for said carriage fixed on said machine against lateral movement, of an instrumentality displaceably mounted on said carriage at the right side thereof so as to be normally free of said track, said instrumentality movable to a position for engaging the right end of said track and arresting the leftward movement of said carriage when it is centered on said machine preparatory to placing the latter in a case, said instrumentality being releasable from engagement with said track by movement of said carriage to the right.

3. In a typewriting machine of the class described, in combination, a main frame, a laterally movable carriage, an escapement-mechanism for said carriage, a track for said carriage including a lateral flange, a carriage-centering member displaceably mounted on said carriage so as to normally clear said flange, and movable downwardly to a position to engage the right end of said flange and arrest the movement of said carriage in one direction when the latter is centered on said machine, a locking piece on said member engaging under said flange and means for connecting said carriage-centering member to said escapement-mechanism so that movement of said member to effective position will release said carriage from said escapement-mechanism.

4. In a typewriting machine, in combination, a main frame, a shift-frame fixed on said main frame against lateral movement, a carriage on said shift-frame movable in letter-feed direction and return, and a normally ineffective carriage-centering device displaceably mounted on said carriage for movement to an effective position for engaging said shift-frame, the engagement of said carriage-centering device with said shift-frame taking place upon movement of said carriage from the right to a position where in it is centered upon said machine, said carriage-centering device becoming disengaged from said shift-frame and ineffective again upon movement of said carriage to the right.

5. In a typewriting machine, the combination with a shift-frame fixed against lateral movement, and a platen-carriage mounted on said shift-frame for movement in letter-feed direction and return, of a centering device displaceably mounted on said carriage and yieldingly held in position to normally move above said shift-frame as said carriage is letter-spaced, said device being movable downwardly to engage said shift-frame and arrest the leftward movement of said carriage when it is centered on said machine, and a locking member on said device engaging said shift-frame for holding said centering device down in effective carriage-arresting position.

6. In a typewriting machine, the combination with a shift-frame fixed against lateral

movement and a platen-carriage mounted on said shift-frame for movement in letter-feed direction and return, of a carriage-centering device displaceably mounted on said carriage and yieldingly held in normal position clear of said shift-frame, said device being movable downwardly to a position wherein it may abut against the right end of a member of said shift-frame upon leftward movement of said carriage to a position wherein it is centered on said machine, and a leftwardly extending locking member on said device disposed for engaging under the right end of said member of said shift-frame when said carriage is centered on said machine, whereby said device is locked in engagement with said shift-frame, said member being releasable upon movement of the carriage to the right.

7. The structure described in claim 6, characterized by said shift-frame member including a lateral and substantially horizontal flange, and said locking member engaging under said flange just before said device abuts against the end of said shift-frame member.

8. In a typewriting machine of the class described, in combination, a shift-frame fixed against lateral movement, a platen-carriage mounted on said shift-frame for movement in letter-space direction and return, a platen-shaft journaled in said carriage, a back plate on said shift-frame fastened between the sides thereof in the rear of said platen-shaft, a forwardly-extending flange-member at the top edge of said plate, a rearwardly-extending carriage-centering lever pivoted about said platen-shaft adjacent the right end of said carriage, yielding means for holding said lever a short distance above said back plate, said lever being depressible to a position whereby it will abut against the right end of said flange when said carriage is moved leftwardly to be centered on said machine, and a leftwardly-extending member on said lever positioned for engaging under said flange when said lever is depressed and said carriage is centered on said machine, said last-named member being effective for retaining said lever and said flange in engagement.

9. In a typewriting machine of the class described, in combination, a carriage, a platen-shaft journaled in said carriage, a carriage-release lever pivoted about said shaft adjacent the right end thereof, a carriage-centering lever pivoted about said shaft and disposed against said release lever, a connection between said levers whereby movement of said carriage-centering lever to effective position will operate said carriage-release lever, and a stop for engaging said carriage-centering lever as said carriage is moved leftwardly upon operation of said carriage-release lever.

10. In a typewriting machine of the class described, in combination, a carriage, a platen-shaft journaled in said carriage, a carriage-release lever pivoted about said shaft adjacent the right end thereof, a carriage-centering lever pivoted about said shaft and disposed against said release lever, a connection between said levers whereby movement of said carriage-centering lever 10 to effective position will operate said carriage-release lever, a stop for engaging said carriage-centering lever as said carriage is moved leftwardly upon operation of said carriage-release lever, a lug on said carriage-centering lever extending laterally in front of the forward edge of said carriage-release lever above its axis, and yielding means urging said centering lever clockwise, whereby counterclockwise movement of said carriage-centering lever will operate said carriage-release lever, and counterclockwise operation of said release-lever may be performed without affecting said centering lever.

11. In a typewriting machine of the class described, in combination, a platen-carriage having strong, rigid end plates, a rearwardly-extending carriage-centering lever loosely pivoted on said carriage adjacent the right hand end plate thereof, said lever being displaceable downwardly, and its rear end portion effective for engaging a laterally fixed member of said machine for arresting said carriage upon movement of the same leftwardly to a position wherein it is centered on said machine, and means for transmitting the blow, taken by said moving lever because of its engagement with said fixed member, to the right-hand rigid end plate.

12. The structure described in claim 11, characterized by said lever including an integral rightwardly-extending lug which terminates in close proximity to said right-hand end plate, said lug being positioned a short distance forward from the portion of said lever which engages said fixed member.

13. In a typewriting machine of the class described, in combination, a platen-carriage having strong, rigid end plates, a rearwardly-extending carriage-centering lever loosely pivoted on said carriage adjacent the right-hand end plate thereof, said lever being displaceable downwardly, and its rear end portion effective for engaging a laterally fixed member of said machine for arresting said carriage upon movement of the same leftwardly to a position wherein it is centered on said machine, means for transmitting the blow, taken by said moving lever because of its engagement with said fixed member, to the right-hand rigid end plate, including an integral rightwardly-extending lug on said lever which terminates in close proximity to said right-hand end plate, said lug being positioned a short distance forward from the portion of said lever which engages said fixed

member, and means for preventing leftward movement of the pivotal end of said moving carriage-centering lever when engaging said fixed member.

14. In a typewriting machine of the class described, in combination, a platen-carriage having stiff unyielding end plates, a platen-shaft on said carriage, a platen on said shaft, a rearwardly-extending carriage-centering lever loosely pivoted about said platen-shaft and displaceable downwardly to make the rear end portion of said lever effective for abutting against a fixed member of said machine upon movement of said carriage leftwardly to a position wherein it is centered on said machine, and means for transmitting to the right-hand end plate the blow taken by said moving lever upon engaging with said fixed member, said means including a collar around said platen-shaft positioned between said platen and the pivotal end of said lever, and a rightwardly-extending lug on said lever terminating in close proximity to said right-hand end plate and positioned to the rear of said collar and adjacent the portion of said lever which strikes against said fixed member.

15. In a typewriting machine of the class described, in combination, a laterally-fixed shift-frame, a platen-carriage movable on said frame in letter-feed direction and return, a displaceable lever mounted on said carriage to move normally above said shift-frame and compressible for engagement with said shift-frame when said carriage, moving leftwardly, is centered on said machine, means for locking said lever and said frame in engagement, and means, upon right-ward movement of said carriage, for restoring said lever to normal position.

16. In a typewriting machine of the class described, in combination, a laterally-fixed shift-frame, a platen-carriage on said frame, a carriage-centering lever on said carriage, means for holding said lever in ineffective position above said frame, including a tensile spring pulling upwardly on said lever and a laterally-disposed feed-roll-release shaft, against which said lever strikes when pulled by said spring, and means for limiting the downward movement of said lever, whereby to bring it into engagement with an upper member of said frame, said limiting means including a portion of said lever extending upwardly in the rear of said shaft, a rearwardly-extending finger-piece on said upwardly-extending portion, and a cross-rod on said carriage against which said finger-piece strikes when said lever has been moved down to position for engaging said upper member.

17. In a typewriting machine having a frame, the combination with a platen-carriage having a propelling spring, an escape-mechanism and a carriage-releaser, of

a projectile carriage-releasing and carriage-centering device mounted on said carriage in normally ineffective position, an abutment on the frame to engage said releasing and centering device when the latter is projected, thereby arresting the released carriage in central position, and means upon the frame to engage said projected device to latch it in projected position when the carriage is centered, said carriage-propelling spring being effective to maintain the carriage in centered position and thereby maintain said device latched in projected position.

18. In a typewriting machine having a frame, the combination with a platen-carriage having a propelling spring, an escape-mechanism and a carriage-releaser, of a projectile carriage-releasing and carriage-centering device mounted on said carriage in normally ineffective position, an abutment on the frame to engage said releasing and centering device when the latter is projected, thereby arresting the released carriage in central position, means upon the frame to engage said projected device to latch it in projected position when the carriage is centered, said carriage-propelling spring being effective to maintain the carriage in centered position and thereby maintain said device latched in projected position, and a spring for restoring said projected device to normal ineffective position when said projected device is released by moving the carriage back.
